UNITED STATES PATENT OFFICE

HORACE J. RICHARDS, OF WATERVLIET, NEW YORK.

OIL-CAN.

SPECIFICATION forming part of Letters Patent No. 416,345, dated December 3, 1889.

Application filed June 5, 1889. Serial No. 313,205. (No model.)

To all whom it may concern:

Be it known that I, HORACE J. RICHARDS, of Watervliet, county of Albany, and State of New York, have invented a new and useful 5 Improvement in Oil-Cans, of which the following is a specification.

My invention relates to improvements in cans for containing oil or other liquids, to adapt them to be carried by a bail and so 10 that they can be turned down on side supports to rest thereon, and with a faucet which will project laterally therefrom when turned down and project vertically when the can rests on the bottom proper and with the bail 15 end uppermost.

Accompanying this specification, to form a part of it, there is a sheet of drawings, containing three figures, illustrating my invention, with the same designation of parts by 20 letter reference used in all of them.

Of these illustrations, Figure 1 shows a perspective of the can with the bail and filling end uppermost. Fig. 2 shows it turned down on its side supports in a condition to 25 have the contents drawn out by a faucet. Fig. 3 shows a cross-section taken through the can and one of its side supports.

The several parts of the can and its attached parts are designated by letter refer- 30 ence, and the function of the parts is de- 35 scribed as follows: The letter C designates the body of the can; T, its cone-formed end, and E what is its bottom end when being carried by the bail B.

The letter T² designates a filling-tube made

in the cone-formed end fitted with a cap t², and F a faucet projected therefrom in a line that is about parallel to the side of the can.

The letters S S designate rectangular supports, which at the ends of their sides S² S² 40 are rigidly attached to each of the sides of the can, and therefrom are extended in a tangential direction to unite at right angles with the support proper S³, on which the can rests when turned down upon its side. This can 45 as thus constructed may be carried by the bail to be filled, and when this has been done it can be placed upon a shelf and turned down to draw from, as required, without tilting.

Having thus described my invention, what I claim, and desire to secure by Letters Patent, is—

The improved oil-can having the rectangular side supports S S, constructed to retain 55 the can in a horizontal position when turned down thereon, the conical end T, having the bail B, and the supply-tube T² and faucet F, projected therefrom in a direction coinciding with the sides of the can, and having the end 60 E at right angles to the sides of the can, substantially in the manner as and for the purposes set forth.

Signed at Troy, New York, this 18th day of April, 1889, in the presence of the two witnesses whose names are hereto written.

HORACE J. RICHARDS.
